[57] CLAIM

The ornamental design for a storm door glass, as shown and described.

DESCRIPTION

FIG. 1 is a perspective view of a storm door glass, showing my new design;

FIG. 2 is a front elevation thereof;

FIG. 3 is a right side elevation thereof, the left side being symmetrical;

FIG. 4 is a rear elevation thereof;

FIG. 5 is a top plan view thereof, the bottom plan view being symmetrical; and,

FIG. 6 is a sectional view of the door, taken on a horizontal plane 6—6 in FIG. 1, showing the surface contour of the inlaid ornamentation.

The broken lines showing a door frame is for illustrative purposes only and form no part of the claimed design.
